UNITED STATES PATENT OFFICE.

MARVIN B. DAVIS, OF KANSAS CITY, MISSOURI, ASSIGNOR TO GEORGE KRELL, OF SAPULPA, OKLAHOMA.

DRAW WORKS.

Application filed April 30, 1926. Serial No. 105,739.

My invention relates to drilling apparatus and more particularly to that portion of a rotary well drilling apparatus known as the draw works.

In drilling apparatus of the above mentioned character a winding drum and the rotary table are generally driven from the same source of power and from the same drive shaft, but as ordinarily constructed, it is impossible to get but a very small, if any, selection of speeds for the driven apparatus from the drive shaft, and if there is any selection this is very difficult to obtain as it involves the moving of chains from one sprocket to the other or some similar act that is difficult to perform.

It is a purpose of my invention to provide new and improved speed changing mechanism in a draw works, whereby a large number of different speeds can be obtained from a drive shaft rotating substantially at a constant speed to drive a winding drum or a rotary table at a large number of different speeds.

My improved draw works preferably is provided with a speed changing mechanism comprising paired gears mounted on a countershaft interposed between the driven apparatus and the drive shaft, said paired gears meshing with other paired gears mounted on the drive shaft. Preferably the gears on the drive shaft are slidably mounted so that the same can be moved into position so that one gear of the pair on the drive shaft will mesh with a gear on the countershaft or the other gear of the pair on the drive shaft will mesh with the other gear on the countershaft to obtain a different speed than would be obtained from the first set of gears meshing. Preferably two pairs of such gears on the drive shaft are provided, which are movable independent of each other to throw one of either pair of gears into mesh with the proper one of a plurality of gears on the countershaft. The gears of one pair are preferably of a different size than the gears of the other pair so as to get four different speeds from the drive shaft in this manner. The spacing of the gears on the countershaft is preferably such that both of the gears of a pair on the drive shaft associated with a pair of gears on the countershaft can be moved to a position that neither of the gears on the drive shaft will mesh with the gears on the countershaft, thus pro-

viding means whereby a gear of either pair can be used for driving without the gears of the other pair being in mesh.

Other objects and advantages of the invention will appear as the description of the accompanying drawings proceeds. However, I desire to have it distinctly understood that I do not intend to limit myself to the exact details shown or described, that I intend to include as part of my invention all such obvious changes and modifications of parts as would occur to a person skilled in this art and as would fall within the scope of the claims.

In the drawings:

Fig. 1 is a perspective view of my improved draw works.

Fig. 2 is a side elevation, partly broken away, thereof, and

Fig. 3 is an end elevation, partly in section, thereof.

Referring in detail to the drawings:

My improved draw works comprises a frame having the lower member 10, the vertically extending members 11 and the top member 12. Mounted in suitable bearings 13 on the vertically extending members 11 is the drive shaft 14 which is provided with a sprocket 15 over which a chain passes for driving said shaft, the chain being driven by any suitable source of power, such as an engine. The shaft 14 is further provided with the intermediate bearings 16 provided on the depending brackets 17 on the member 12. The outer ends of the shaft 14 may be provided with suitable winches or winding drums 18.

Mounted on the shaft 14 are the paired gears 19-20 and 21-22. Said gears 19 and 20 are mounted so as to rotate together and are slidably mounted on the shaft 14, engaging with the key 23 thereon so as to always rotate with said shaft. The gears 21 and 22 are also mounted so as to rotate together and also engage with the key 23 in the same manner as do the gears 19 and 20. The gears 19 and 21 are provided with grooved collars or grooved hub portions 24 and 25 respectively, with which the pins 26 and 27 on the levers 28 and 29 engage. The levers 28 and 29 are pivoted respectively at 30 and 31 on the member 12, the member 28 being provided with an operating rod 32 having the handle 33, and the member 29 being provided with an operating rod 34 having the handle 35.

35. The grooved collars 24 and 25 are each provided with a link 36 that is pivoted to the frame and each link has a pin 37 extending into the groove in each of said collars for properly supporting the same in position and guiding the same in their movements on the shaft 14.

The vertically extending members 11 are also provided with the bearings 38 upon 10 which the countershaft 39 is mounted, said countershaft also having the central bearing members 40 mounted on the bracket members 17. The countershaft is provided with a gear 41 that is adapted to mesh with the gear 19, a gear 42 that is adapted to mesh with the gear 20, a gear 43 that is adapted to mesh with the gear 21 and a gear 44 that is adapted to mesh with the gear 22, said gears being all fixed in position on the 15 countershaft 39 and mounted to rotate therewith. The countershaft 39 is further provided with a bevel gear 45 meshing with the bevel gear 46 that is provided on the vertically extending shaft 47 which is mounted 20 in the bearing brackets 48 and 49 provided on one of the vertically extending members 11. The lower end of the shaft 49 is provided with a bevel gear 50 that meshes with a bevel gear 51 provided on the shaft 52. 25 Said shaft 52 is provided with a clutch of any suitable form 53, operated by the actuating lever 54 for connecting the shaft 52 with the shaft 55, said shaft 55 being provided with a flexible coupling 56 connecting 30 the same with a shaft 57 that is provided with a bevel gear 58 meshing with the gear teeth 59 provided on the under side of the rotary table 60.

The gear 42 meshes with a gear 61 that 40 is mounted to rotate freely on the shaft 62 mounted in the bearings 63 on the members 11. A clutch member 64 is provided on the gear wheel 61 that meshes with a cooperating clutch member 65 connected with the 45 shaft 62 when the same is moved into engagement with the member 64 by means of the yoke 66 having pins 67 operating in the groove 68 on the clutch member 65, said member being movable into position by 50 means of the lever 69 pivoted on the ears 70 on one of the members 11. When the clutch members 64 and 65 are in mesh, the drum 71 is rotated due to rotation of the shaft 62 along with the gear 61. When 55 the clutch members are disengaged, however, the drum 71 is not rotated by the gearing, and if it is desired to slow down or stop the rotation of the same, the band brake members 72 engaging with the flanges 73 60 on the drum 71 are actuated by means of the lever 74 having the shaft-like portion 75 provided with the crank members 76 thereon, to engage the band members 72 with the flanges 73 either to slow down or 65 stop the rotation of the drum 71. Springs

77 are provided extending from the ears 78 on the band members 72 to the collars 79 mounted on the countershaft 39, which tend to hold the band 72 away from the surface of the flanges 73.

It will be obvious that either the clutch comprising the members 64 and 65 or the clutch 53 can be operated to stop the rotation of the drum 71 or the rotary table 60. The spacing of the gears is such that both 75 of the gears 21 and 22 can lie between the gears 43 and 44 and both of the gears 19 and 20 can lie between the gears 41 and 42. Accordingly any gear can be connected with the gear capable of co-operating therewith, 80 without throwing any of the other gears in mesh, to obtain any one of four different speeds of rotation of the countershaft 39 relative to the drive shaft 14, and thus of the drum 71 or the rotary table 60 relative 85 to the drive shaft 14 and relative to the engine or other driving means provided for rotating the shaft 14. Thus a very quickly changeable connection is provided between the driving shaft and the members to be 90 driven thereby, giving a much greater selection as well as a much more easily operable driving means than has been previously known.

What I claim and desire to secure by 95 Letters Patent is:

1. In well drilling apparatus, draw works comprising a drive shaft having a drive wheel thereon for rotating the same, means for driving a rotary table, means for driving a winding drum and a change speed mechanism interposed between said drive shaft and said driving means, comprising a countershaft, and paired gears on said drive shaft and countershaft, the paired gears on 100 one of said shafts being slidably mounted to move the same into and out of engagement selectively with either of the gears of a pair on the other shaft.

2. In well drilling apparatus, draw works 110 comprising a drive shaft having a drive wheel thereon for rotating the same, means for driving a rotary table, means for driving a winding drum and a change speed mechanism interposed between said drive shaft 115 and said driving means, comprising a countershaft, a plurality of sets of paired gears on each of said shafts, the gears on one of said shafts being slidably mounted in pairs thereon, and the paired gears being so relatively spaced that one of said sets may be out of mesh when either of the gears of the other pair is in mesh with the gear corresponding thereto on the other shaft.

3. In well drilling apparatus, a drive shaft 125 having a drive sprocket thereon, pairs of gears slidably mounted thereon, a countershaft, gears on said countershaft with which said gears on said drive shaft are adapted to mesh selectively, a winding drum shaft, a 130

- winding drum gear mounted thereon and geared to said countershaft, a shaft for driving a rotary table, and means for driving said last mentioned shaft from said countershaft.
- 5 4. In well drilling apparatus, a drive shaft having a drive sprocket thereon, pairs of gears slidably mounted thereon, a countershaft, gears on said countershaft with which said gears on said drive shaft are adapted to mesh selectively, a winding drum shaft, a winding drum gear mounted thereon and geared to said countershaft, a shaft for driving a rotary table, and means for driving said last mentioned shaft from said countershaft.
- 10 5. In well drilling apparatus, a drive shaft having a drive sprocket thereon, pairs of gears slidably mounted thereon, a countershaft, gears on said countershaft with which said gears on said drive shaft are adapted to mesh selectively, a winding drum shaft, a winding drum gear mounted thereon and meshing with one of the gears on said countershaft, a shaft for driving a rotary table, and means for driving said last mentioned shaft from said countershaft.
- 15 6. In well drilling apparatus, a drive shaft having a drive sprocket thereon, pairs of gears slidably mounted thereon, a countershaft, gears on said countershaft with which said gears on said drive shaft are adapted to mesh selectively, a winding drum shaft, a winding drum gear mounted thereon and meshing with one of the gears on said countershaft, a shaft for driving a rotary table, and means for driving said last mentioned shaft from said countershaft.
- 20 7. In well drilling apparatus, a drive shaft having a drive sprocket thereon, pairs of gears slidably mounted thereon, a countershaft, gears on said countershaft with which said gears on said drive shaft are adapted to mesh selectively, a winding drum shaft, a winding drum gear mounted thereon and meshing with one of the gears on said countershaft, a shaft for driving a rotary table, and means for driving said last mentioned shaft from said countershaft, said last mentioned means comprising an intermediate, 50 vertically extending shaft geared to said rotary table driving shaft and a pair of bevel gears connecting said countershaft with said vertically extending shaft.
- 25 30 In testimony whereof I affix my signature.
MARVIN B. DAVIS.
